UNITED STATES PATENT OFFICE.

CHARLES C. GRUHLER, OF FORT THOMAS, KENTUCKY.

ENVELOPE OPENER.

Application filed January 24, 1927. Serial No. 163,100.

The invention relates to improvements in devices for cutting or trimming paper and the like and the present disclosure is directed to such a device designed primarily for use in opening envelopes.

It is one object of the invention to provide a device of the class set forth which is simple and inexpensive and embodies unique means for limiting the movement of the trimming knife. In the present disclosure, a portion of the limiting means also co-acts with a spring which normally raises the knife to an inoperative position.

Another aim of the invention is to provide a tension spring disposed in a novel manner to prevent springing of the knife away from the straight edge with which it co-acts.

With the foregoing in view, the invention resides in the novel subject matter herein-after described and claimed, the description being supplemented by the accompanying drawing.

Fig. 1 is a perspective view of the complete device.

Fig. 2 is a perspective view of the knife.

Figs. 3 and 4 are vertical transverse sections on lines 3—3 and 4—4 of Fig. 1.

In the drawing above briefly described, the numeral 5 designates an appropriate base which may be of the design shown or if desired may be hollow. This base is provided with a longitudinal slot 6, at least one edge of which is straight for co-action with a horizontally elongated knife 7. In the present showing, one end of this knife contacts with one side of a vertical plate 8 which rises rigidly from the base 5, said plate being preferably provided with a base flange 9 secured by appropriate fasteners 10 to said base. A pivot stud 11 extends from the knife 7 through an opening in the plate 8 and is provided on its outer end with a nut or the like 12. A coiled compression spring 13 surrounds the stud 11 between the plate 8 and the nut 12 and so bears against the latter as to hold the knife 7 in contact with the plate 8, in such position that the pivoted end of the knife will properly coact with the straight edge of the slot 6. To hold the other end of the knife against springing away from this straight edge, I provide a coiled tension spring 14 having

one end connected at 15 with the knife, while its other end is suitably anchored at 16 to the base, said spring being disposed transversely of the base and serving to pull the knife toward the straight edge of the slot 6.

The upper end of the plate 8 is formed with a notch 17 having vertical ends 18 and 19 constituting stops for a purpose to appear. A horizontal lug 20 which is rigid with the upper edge of the knife 7, projects through the notch 17 and is co-operable with the notch edges 18 and 19 to limit both the upward and the downward movement of said knife. One end 21 of the spring 13 is seated in a notch 22 in one edge of the lug 20 and the other end 23 of said spring bears 70 against the flange 9, said spring having sufficient torsional strength to act upon the lug 20 and normally raise the knife 7, until said lug strikes the stop 18 formed by one vertical edge of the notch 17. With the knife 75 thus held in raised position, an envelope or the like may be inserted beneath it. Then, by pressing upon a suitable knob 24 at the free end of the knife, the latter may be depressed to perform the cutting operation. 80 Such depression of the knife is limited by the lug 20 coming in contact with the second shoulder 19.

A guard 25 is preferably secured to the base at the front of the knife 7 and is cut away at its lower portion as at 26 to permit the passage of an envelope or the like beneath it. A rear guard 27 is by preference employed to limit the extent to which the envelope or the like may be inserted under 90 the knife 7. This rear guard is by preference provided with brackets 28 having slots 29 through which thumb screws 30 pass to secure the guard to the base 5. By loosening these thumb screws, the guard 27 may be adjusted toward or from the slot 6 to vary the amount which may be trimmed from envelopes or analogous objects.

It will be seen from the foregoing that while the invention is simple and inexpensive, it will be efficient and very desirable, and as excellent results may be obtained from the details disclosed, such details may well be followed. However, within the scope of the invention as claimed, variations may 105 be made. For instance, while the plate 8

and the guard 25 are herein shown as formed separately, they might in some instances be connected integrally.

I claim:

- 5 1. In a trimming device, a base, a plate secured to and rising rigidly from said base, the upper edge of said plate having a notch, a trimming knife having one of its end portions disposed at one side of said plate, a pivot for said knife connecting it with said plate, and a lug rigid with said knife and projecting laterally therefrom through the aforesaid notch, said lug being co-operable with an end of said notch to limit the movement of the knife.
- 10 2. In a trimming device, a base, a plate secured to and rising rigidly from said base, the upper edge of said plate having a notch, a trimming knife having one of its end portions disposed at one side of said plate, a pivot for said knife connecting it with said plate and projecting laterally from the latter, a lug rigid with said knife and projecting laterally therefrom through the
- 15 20

aforesaid notch, and a spring wound around said pivot and having an end engaged with said lug to raise the knife until the lug strikes one end of said notch.

3. In a trimming device, a base, a plate secured to and rising rigidly from said base, the upper edge of said plate having a notch, a trimming knife having one of its end portions disposed at one side of said plate, a pivot for said knife connecting it with said plate, a pivot for said knife connecting it with said plate and projecting laterally from the latter, a lug rigid with said knife and projecting laterally therefrom through the aforesaid notch, and a spring wound around said pivot and having an end engaged with said lug to raise the knife until the lug strikes one end of said notch, the other end of the notch and the lug being co-operable to limit the depression of the knife.

In testimony whereof I have hereunto affixed signature.

CHARLES C. GRUHLER.
